Roy S. Sanford

BY
Dr. W. M. Conkey
ATTORNEY

UNITED STATES PATENT OFFICE

ROY S. SANFORD, OF SOUTH BEND, INDIANA, ASSIGNOR TO BENDIX BRAKE COMPANY,
OF SOUTH BEND, INDIANA, A CORPORATION OF ILLINOIS

BRAKE

Application filed March 21, 1928. Serial No. 263,404.

This invention relates to brakes, and is illustrated as embodied in an internal expanding automobile brake. An object of the invention is to permit a shoe, or one of a 5 pair of shoes or the like friction devices, to adjust its position to compensate for wear by pivotally mounting it on means such as a pivoted rigid compression link, for example by frictionally clamping the shoe to the link adjacent the center of the shoe. In embodying 10 the invention in a connection between two shoes, the above-described link is arranged to operate the second shoe, which is illustrated as one of the anchored shoes of a three-shoe brake.

The above and other objects and features of the invention, including various novel combinations of parts and desirable details of construction, will be apparent from the 20 following description of one illustrative embodiment shown in the accompanying drawings, in which:

Figure 1 is a view showing the brake in vertical section, just inside the head of the 25 brake drum, with the brake shoes in side elevation, and also showing part of the operating mechanism in side elevation; and

Figure 2 is a partial section, on the line 2—2 of Figure 1, through the means connecting the shoe and link.

The illustrated brake mechanism includes a rotatable brake drum 10, at the open side of which is a backing plate or other support 12, and within which is arranged novel friction means such as three brake shoes 14, 16, and 18 operated by an applying device such as a cam 20. Cam 20 is shown integral with a shaft journaled in a bracket carried by the backing plate 12, and having an arm 22 connected by a brake rod 24 with the operating mechanism on the chassis.

One form of operating mechanism, shown in the drawing, includes a hand lever 26 having a slot 28 embracing a pivot pin 30, and 45 having a pawl 32 rigid with the lever. A leaf type spring 34 urges pawl 32 against a ratchet 36 curved about pin 30 as a center. The above-described lever 26 and associated parts are mounted on the chassis frame 38. 50 The shoes 14, 16, and 18, in the form shown,

are built up of L-section stampings riveted or welded back to back and carrying suitable brake lining, as shown in Figure 2. The stampings forming shoe 18 are spread apart at the lower end of the shoe, to straddle shoe 16, thus in effect causing these two shoes to overlap.

Shoes 16 and 18 are preferably anchored on pivots 40 and 42 carried by the backing plate 12. The brake is applied by means of cam 20 or its equivalent spreading shoes 14 and 18 apart against the resistance of a return spring 44, and shoe 16 is applied by shoe 14 against the resistance of an auxiliary return spring 46. An eccentric adjustable stop 48 engaging the unanchored end of shoe 16 serves to determine the released position of that shoe.

According to an important feature of the present invention, the connection between 70 shoes 14 and 16 includes one or a pair of compression links 50 freely connected to an intermediate portion of shoe 16 by a pivot 52. These links embrace between them, at their opposite ends, the central stiffening web of shoe 14, preferably adjacent its center. The links are connected to shoe 14 by means such as a pivot or bolt 54, illustrated as having at one end a nut 56 compressing a coil spring 58 urging friction washers 60 80 against opposite sides of the shoe stiffening web. These parts constitute friction means clamping the shoe to the links, and permitting the shoe to turn with respect to the links when the brake is applied, to compensate automatically for wear, while preventing the shoe from turning at all other times.

While one illustrative embodiment of the invention has been described in detail, it is not my intention to limit the scope of the 90 invention to that particular embodiment, or otherwise than by the terms of the appended claims.

I claim:

1. A brake comprising a pair of rigid shoes arranged end to end, in combination with a rigid link freely pivoted to one shoe and frictionally clamped to the other shoe. 95
2. A brake comprising a pair of rigid shoes arranged end to end, in combination with a 100

rigid link freely pivoted to one shoe and frictionally pivoted to the other shoe.

3. A brake comprising, in combination, three shoes arranged end to end, anchoring means engaging adjacent ends of two of the shoes, a compression link pivotally connected to one of the anchored shoes and frictionally clamped to the third shoe, and applying means acting on said third shoe and on the other of the anchored shoes.

4. A brake comprising in combination, a drum, a friction device engageable with the drum, brake operating means constructed and arranged to contact said friction device at one end thereof, and a swinging rigid link pivotally mounted at one end and frictionally clamped to said friction device at its other end.

5. A brake comprising in combination, a drum, a friction device engageable with the drum, means for actuating the friction device, said means acting on a portion of the device remote from the central portion thereof together with anchor means for taking the thrust of said friction device, said anchor means being so connected to said device as to move therewith as a unit during the releasing movement of the brake and yet being capable of relative angular movement with respect thereto during the application of the brake.

In testimony whereof, I have hereunto signed my name.

ROY S. SANFORD.
